(57) **CLAIM**

The ornamental design for a wrap around walking aid, as shown and described.

DESCRIPTION

FIG. 1 is a front isometric view of a wrap around walking aid in a first orientation.

FIG. 2 is a back isometric view of the wrap around walking aid in the first orientation.

FIG. 3 is a front view of the wrap around walking aid in the first orientation.

FIG. 4 is a back view of the wrap around walking aid in the first orientation.

FIG. 5 is a right side view of the wrap around walking aid in the first orientation.

FIG. 6 is a left side view of the wrap around walking aid in the first orientation.

FIG. 7 is a top view of the wrap around walking aid in the first orientation.

FIG. 8 is a bottom view of the wrap around walking aid in the first orientation.

FIG. 9 is a front isometric view of a wrap around walking aid in a second orientation.

FIG. 10 is a back isometric view of the wrap around walking aid in the second orientation.

FIG. 11 is a front view of the wrap around walking aid in the second orientation.

FIG. 12 is a back view of the wrap around walking aid in the second orientation.

FIG. 13 is a right side view of the wrap around walking aid in the second orientation.

FIG. 14 is a left side view of the wrap around walking aid in the second orientation.

FIG. 15 is a top view of the wrap around walking aid in the second orientation; and,

FIG. 16 is a bottom view of the wrap around walking aid in the second orientation.

1 Claim, 14 Drawing Sheets
